DESIGN FOR A CLASP FOR SANITARY NAPKINS

Thomas Edward Hicks, Princeton, N. J., assignor to The Modess Corporation, New York, N. Y., a corporation of New Jersey

Application October 6, 1934, Serial No. 53,510

Term of patent 7 years

To all whom it may concern:

Be it known that I, Thomas Edward Hicks, a citizen of the United States, residing at Princeton, in the county of Mercer and State of New Jersey, have invented a new, original, and ornamental Design for a Clasp for Sanitary Napkins, of which the following is a specification, reference being had to the accompanying drawing, forming part thereof.

I claim:

The ornamental design for a clasp for sanitary napkins substantially as shown.

THOMAS EDWARD HICKS.
